UNITED STATES PATENT OFFICE.

PHILIP LINDEMAYER, OF BALTIMORE, MARYLAND, ASSIGNOR TO THE
MONARCH MANUFACTURING COMPANY, OF SAME PLACE.

DESIGN FOR A BOTTLE.

SPECIFICATION forming part of Design No. 28,841, dated June 14, 1898.

Application filed April 15, 1898. Serial No. 677,751. Term of patent 7 years.

To all whom it may concern:

Be it known that I, PHILIP LINDEMAYER, a resident of Baltimore city, in the State of Maryland, have invented certain new and useful 5 Improvements in a Design for Bottles; and I do hereby declare the following to be a full, clear, and exact description of the invention, such as will enable others skilled in the art to which it pertains to make and use the 10 same.

Figure 1 is a perspective view of a bottle embodying the new design. Fig. 2 is a longitudinal section of the bottle.

As shown in the drawings, the leading or 15 material feature of my design consists of a bottle having a terminal comprising the frusto-conical neck 1, surmounted by a similarly-formed head 2 of less diameter.

3 indicates a shoulder intermediate the head and neck. 20

4 4 indicate grooves in the neck, which extend up to the shoulder, as shown.

Referring to Fig. 2, the usual opening of a bottle-mouth is denoted by 5, and 6 indicates a lip in plan view, and 7 is a plan of the shoulder 25 3.

Having described my invention, I claim—

The design for a bottle as herein shown and described.

In testimony whereof I have signed this 30 specification in the presence of two subscribing witnesses.

PHILIP LINDEMAYER.

Witnesses:

WILLIAM W. YOUNG,
FRANK D. BLACKSTONE.
